[57] CLAIM

The ornamental design for an air freshener for mounting on a blade of a ceiling fan, as shown and described.

DESCRIPTION

FIG. 1 is a top perspective view of an air freshener for mounting on a blade of a ceiling fan, showing my new design;

FIG. 2 is an enlarged top plan view thereof;

FIG. 3 is an enlarged bottom plan view thereof;

FIG. 4 is an enlarged end elevation view thereof, the opposite end being a mirror image of that shown;

FIG. 5 is an enlarged front elevation view thereof, the rear being a mirror image of that shown;

FIG. 6 is an enlarged top plan view thereof in open position; and,

FIG. 7 is an enlarged front elevation view thereof in open position.

The broken line showing of environmental structure in FIG. 1 is for illustrative purposes only and forms no part of the claimed design.
